UNITED STATES PATENT OFFICE.

JOSEPH H. SEBALD, OF ARLINGTON, NEW JERSEY, ASSIGNOR TO HENRY R. WORTHINGTON, OF NEW YORK, N. Y., A CORPORATION OF NEW JERSEY.

MULTIPLE-EXPANSION ENGINE.

1,124,339.

Specification of Letters Patent.

Patented Jan. 12, 1915.

Application filed August 4, 1909. Serial No. 511,143.

To all whom it may concern:

Be it known that I, JOSEPH H. SEBALD, a citizen of the United States, residing at Arlington, county of Essex, and State of New Jersey, have invented certain new and useful Improvements in Multiple-Expansion Engines, fully described and represented in the following specification and the accompanying drawings, forming a part of the 10 same.

This invention relates especially to vertical triple expansion duplex pump engines of that class having the cylinders on each side arranged in line, the especial object of the 15 invention being to provide an improved arrangement of pistons, piston rods, and cross head for vertical engines of this class. The invention includes, however, certain broad features which may be applied also in single 20 engines or in horizontal engines.

In the accompanying drawing forming a part of this specification, there is shown for the purpose of illustration a vertical duplex pumping engine embodying all the 25 features of the invention in a preferred form and this construction will now be described in detail and the features forming the invention specifically pointed out in the claims.

Referring to the drawing, which shows 30 the pumping engine with one side in elevation and the other side partly in section taken centrally through the steam and pump ends, A, B, C are respectively the high pressure, intermediate pressure, and low pressure cylinders having the corresponding pistons a, b, c, and D the water cylinders on each side of the engine having the plungers d. The low pressure pistons c are connected to plungers d by rods 14, heads 15 and side 35 rods 16, liquid balancing cylinder E and balancing piston e being shown, although it will be understood that these features are not essential to the present invention.

Any suitable construction may be used for 40 controlling the admission and exhaust of steam, employing either separate cut off valves or combined admission and cut off valves, and cut off valves may or may not be used on the intermediate cylinders as 45 preferred. In the construction shown, cut off valves are used only on the high pressure cylinder and separate cut off valves are employed, the construction and operating connections of the valves indicated being 50 the same as that of United States Letters 55

Patent to Brown No. 746,667, dated December 15, 1903, the valve cranks being connected by links 10 so as to be operated from cross over rock shafts 11 which are preferably arranged between the high and intermediate pressure cylinders, all as in said Letters Patent No. 746,667.

Referring now to the arrangement of the steam end, the low pressure piston c on each side is connected by side rods 17 to cross head 18 to which the high pressure piston a is connected by rod 19. This cross head is preferably placed, as shown, between the high pressure and intermediate pressure cylinders A, B, which are separated sufficiently for the movement of the cross head, and the high pressure piston rod 19 passes through the inner or lower end of the high pressure cylinder A. Intermediate pressure piston b is connected by rod 20 passing through the inner or lower end of the cylinder B to the low pressure piston c. The side rods 17 thus carry only the power of the high pressure piston, and each of the piston rods thus transmits only the power of a single cylinder, the power of the three cylinders being transmitted from the low pressure piston c to the plunger through heavy rod 14. The low pressure piston c is accessible and removable through lower or inner head 1, the intermediate piston b through upper or outer head 2, which may be a separate head or a part of the cradle carrying the high pressure cylinder, and the high pressure piston a through upper or outer head 3. The cross heads 18 actuate the cross over rock shafts 11 through arms 4 on the cross heads and the usual levers 5 on the rock shaft.

It will be seen that, in the construction shown, each of the pistons is readily accessible and removable, convenient means are provided for actuating the valve motion, the number of stuffing boxes is reduced to the minimum, and light piston rods may be used throughout the steam end, as there is only the load of one piston on any rod, except the plunger rod 14 through which the engine power is transmitted, and the outside rods to the cross heads carry only the high pressure piston load. The invention provides a very convenient, compact and efficient construction of duplex engine in which the valve movement is operated without any extra rod from the low pressure piston, or

other extra parts, but directly from the cross head through which the power of the high pressure piston is transmitted.

It is to be understood that the invention is not to be limited to the exact construction or arrangement of parts shown, but that modifications may be made within the invention, as defined by the claims, and that the broader features of the invention may be applied to engines having more than 10 three cylinders.

What I claim is:—

1. A multiple expansion engine having three cylinders arranged in line in the order of expansion with the low pressure cylinder placed inside and the power applied from the low pressure piston, a rod connecting the intermediate pressure piston and low pressure piston, a cross head to which the high pressure piston is connected by a rod passing through one head of the high pressure cylinder, and side rods connecting the cross head with the low pressure piston.

2. A multiple expansion engine having three cylinders arranged in line in the order of expansion with the low pressure cylinder placed in side and the power applied from the low pressure piston, a rod connecting the intermediate pressure piston and low pressure piston, a cross head between the high pressure cylinder and intermediate pressure cylinder to which the high pressure piston is connected by a rod passing through the inner head of the high pressure cylinder, and side rods connecting the cross head with the low pressure piston.

3. In a multiple expansion duplex engine, the combination of three cylinders on each side arranged in line in the order of expansion with the low pressure cylinder placed

inside and the power applied from the low pressure piston, rods connecting the intermediate pressure pistons and low pressure pistons, cross heads to which the high pressure pistons are connected by rods passing through one head of the high pressure cylinders, side rods connecting the cross heads with the low pressure pistons, rock shafts extending across the engine and connected to the valves for operating the valves on each side of the engine from the other side, and operating connections between the cross heads and rock shafts.

4. In a multiple expansion duplex engine, the combination of three cylinders on each side arranged in line in the order of expansion with the low pressure cylinder placed inside and the power applied from the low pressure piston, rods connecting the intermediate pressure pistons and low pressure pistons, cross heads between the high pressure cylinders and intermediate pressure cylinders to which the high pressure pistons are connected by rods passing through the inner heads of the high pressure cylinders, side rods connecting the cross heads with the low pressure pistons, rock shafts extending across the engine between the high pressure cylinders and intermediate pressure cylinders for operating the valves on each side of the engine from the other side, and operating connections between the cross heads and rock shafts.

In testimony whereof, I have hereunto set my hand, in the presence of two subscribing witnesses.

JOSEPH H. SEBALD.
